UNITED STATES PATENT OFFICE

PAUL S. SHIELD, OF CINCINNATI, OHIO, ASSIGNOR TO AUGUSTINE DAVIS, JR., OF CINCINNATI, OHIO

TANK DELIVERY STRUCTURE

Application filed March 20, 1926. Serial No. 96,236.

This invention relates to safety delivery systems for tanks, for example such as gasoline truck tanks, the liquid, instead of passing from a bottom outlet, being drawn off through a siphon or siphon-like system. The purpose of the invention is to provide an especially economical, efficient and reliable construction.

In the accompanying drawings, forming part hereof:

Fig. 1 is a side elevation of a tank embodying the invention, an intermediate part of the tank being broken out because of lack of space;

Fig. 2 is a vertical, transverse section taken in the axial plane of one of the uptake pipes; and

Fig. 3 is a horizontal cross-section on the line 3—3 of Fig. 2.

The tank shown in Fig. 1 comprises a plurality of compartments or tank chambers 2, and at the rear end there may be a box 3, termed a bucket-box.

In each chamber there is an uptake pipe 4, having its open lower end in a bottom pocket 5, and stayed at the foot by a suitable spider 6.

The pipe 4 passes upward through the bottom of a box 7 of larger diameter, the upper end of the pipe terminating in this box, which is secured in a flanged opening 8 in the top of the tank shell. The body of this box is advantageously made of a tubular piece 9, consisting of a short length of large pipe. The side of this member is welded to the shell at 10, with a portion of the member projecting above the shell; and in the lower end of the member an annular pipe 11 is welded, forming the bottom of the box. The pipe 4 is secured by welding in the opening of the bottom piece.

An opening 12 is formed in the tubular piece 11, adjacent the bottom, and at this opening is welded or otherwise secured an outlet pipe 13, which is shown extending downward within the tank to join a manifold 14, said manifold passing to the rear through the wall of the tank chambers, and terminating at the bucket-box in a suitably

valved outlet 15 adapted to receive a delivery hose.

A flanged thimble 16 having a horizontal top flange 17 is telescoped over the projecting upper end of the tubular piece 9 and there welded, the thimble thus forming part of the box heretofore referred to.

The upper end of the uptake pipe 4 is screw-threaded, and screwed on this portion is a valve-seat ring 18. The valve-seat, and the upper end of the pipe, are accurately centered and braced in the box by a spider 19, the arms of which extend from an upper ring 20 downward to the ring 18, being integral with both. The ring 20 closely fits the interior of the thimble, and by resting on a shoulder 21 in this thimble affords an additional, suspensional support for the uptake pipe, taking part of the stresses of jolting, etc. from the welds which unite the pipe 4 with the lower end of the box, and more directly taking the shock of the spring closing of the valve on the seat.

A cover 22 is removably applied to the thimble 16, being tightly bolted to the flange 17 by screws 23. A downwardly projecting circular rib 24 on this cover enables it to be centered accurately on the thimble, from which, in turn, the valve-seat 18 is centered.

The cover 22 has a stuffing-box 25 and a downwardly projecting guide bearing 26, for the stem 27 of a poppet valve 28, which seats downwardly on the valve-seat under the action of a spring 29.

The protruding upper end of said valve-stem is arranged to be acted upon by one arm of a bell-crank rocker 30, which is pivoted in a superstructure 31 on the cover. An operating or control mechanism of the kind disclosed in my copending application filed of even date herewith, Serial No. 96,235 is illustrated. This mechanism need not be specifically described here; but it may be stated that the rockers 30 are actuated through levers 32 to lift the valves, said levers being operable by dogs 33 on a common turnable and longitudinally movable control rod 34.

While the preferred embodiment of the

invention has been described in detail, it will be understood that I do not wish to limit myself to the precise form, since various changes may be made within the scope of the claims.

5. I claim:

1. In a tank, siphon means for emptying the tank comprising a box secured in the top of the tank, and an uptake pipe and an outlet pipe communicating with the interior of said box, one of said pipes being united to said box and projecting upward in the interior thereof, a valve-seat applied to the upper end of this pipe, and a single spider positioning said valve seat in the box and bracing the upper end of said pipe.
10. In a tank, siphon means for emptying the tank comprising a box secured in the top of the tank, and an uptake pipe and an outlet pipe communicating with the interior of said box, one of said pipes being united to said box and projecting upward in the interior thereof, and a spider member having two rings, one fitting the interior of the box and the other being a valve-seat which is applied to the upper end of said pipe.
15. In a tank, siphon means for emptying the tank comprising a box secured in the top of the tank, and an uptake pipe and an outlet pipe communicating with the interior of said box, one of said pipes being united to said box and projecting upward in the interior thereof, and a spider member having two rings, one fitting the interior of the box and the other being a valve-seat which is applied to the upper end of said pipe.
20. In a tank, siphon means for emptying the tank comprising a box secured in the top of the tank, and an uptake pipe and an outlet pipe communicating with the interior of said box, one of said pipes being united to said box and projecting upward in the interior thereof, and a spider member having two rings, one fitting the interior of the box and the other being a valve-seat which is applied to the upper end of said pipe.
25. In a tank, siphon means for emptying the tank comprising a box secured in the top of the tank, and an uptake pipe and an outlet pipe communicating with the interior of said box, one of said pipes being united to said box and projecting upward in the interior thereof, and a spider member having two rings, one fitting the interior of the box and the other being a valve-seat which is applied to the upper end of said pipe.
30. In a tank, siphon means for emptying the tank comprising a box secured in an opening in the top of the tank, and an uptake pipe and an outlet pipe communicating with the interior of said box, one of said pipes passing upwardly within said box member and secured to the bottom thereof, a thimble secured on the upper end of said box member outside of the tank, a valve-seat applied to the upper end of said pipe, with a spider centering said valve-seat and bracing the upper end of said pipe from said thimble, a cover for said thimble, and a valve carried by said cover to coact with said valve-seat.
35. In a tank, siphon means for emptying the tank comprising a box secured in an opening in the top of the tank, and an uptake pipe and an outlet pipe communicating with the interior of said box, one of said pipes passing upwardly within said box member and secured to the bottom thereof, a thimble secured on the upper end of said box member outside of the tank, a valve-seat applied to the upper end of said pipe, with a spider centering said valve-seat and bracing the upper end of said pipe from said thimble, a cover for said thimble, and a valve carried by said cover to coact with said valve-seat.
40. In a tank, siphon means for emptying the tank comprising a box secured in the top of the tank, and an uptake pipe and an outlet pipe communicating with the interior of said box, one of said pipes passing through and being united to the wall of said box and being provided at its upper end with a valve seat, supporting means seated in the box and engaging the upper portion of said pipe, and a valve guided in the box to close against the valve seat at the upper end of said pipe.
45. In a tank, siphon means for emptying the tank comprising a box secured in the top of the tank, and an uptake pipe and an outlet pipe communicating with the interior of said box, one of said pipes passing through and being united to the wall of said box and being provided at its upper end with a valve seat, supporting means seated in the box and engaging the upper portion of said pipe, and a valve guided in the box to close against the valve seat at the upper end of said pipe.
50. In a tank, siphon means for emptying the tank comprising a box secured in the top of the tank, and an uptake pipe and an outlet pipe communicating with the interior of said box, one of said pipes passing through and being united to the wall of said box and being provided at its upper end with a valve seat, supporting means seated in the box and engaging the upper portion of said pipe, and a valve guided in the box to close against the valve seat at the upper end of said pipe.
55. In a tank, siphon means for emptying the tank comprising a box secured in the top of the tank, and an uptake pipe and an outlet pipe communicating with the interior of said box, one of said pipes passing through and being united to the wall of said box and being provided at its upper end with a valve seat, supporting means seated in the box and engaging the upper portion of said pipe, and a valve guided in the box to close against the valve seat at the upper end of said pipe.
60. In a tank, siphon means for emptying the tank comprising a box secured in the top of the tank, and an uptake pipe and an outlet pipe communicating with the interior of said box, one of said pipes passing through and being united to the wall of said box and being provided at its upper end with a valve seat, supporting means seated in the box and engaging the upper portion of said pipe, and a valve guided in the box to close against the valve seat at the upper end of said pipe.
65. In a tank, siphon means for emptying the tank comprising a box secured in the top of the tank, and an uptake pipe and an outlet pipe communicating with the interior of said box, one of said pipes passing through and being united to the wall of said box and being provided at its upper end with a valve seat, supporting means seated in the box and engaging the upper portion of said pipe, and a valve guided in the box to close against the valve seat at the upper end of said pipe.
